UNITED STATES PATENT OFFICE.

WILFRED O. CHASE, OF REDFORD, MICHIGAN, ASSIGNOR TO STEWART-WARNER SPEEDOMETER CORPORATION, OF CHICAGO, ILLINOIS, A CORPORATION OF VIRGINIA.

VACUUM FUEL-FEEDING SYSTEM.

Application filed October 8, 1921, Serial No. 506,266. Renewed March 20, 1926.

The invention relates to vacuum feeding systems and has for its object simplifying the construction and improving and rendering more certain the operation.

In the present state of the art various constructions of vacuum feeding apparatus have been devised, all of which have certain elements in common. Thus there is present in each construction a low level tank, a high level or vacuum tank usually having two compartments, the upper compartment being directly connected with the low level tank and having a gravity discharge connection to the lower compartment controlled by a normally closed check-valve, a suction connection between the intake manifold of the engine and the upper chamber, an air inlet for the upper chamber and valves which alternatively open and close the suction and air inlet connections, the operating mechanism for these valves consisting of a float arranged in the upper chamber together with a lever and spring mechanism by which the movement of the float will at predetermined upper and lower levels cause a reversal of the valves. Thus the upper chamber will periodically receive fuel from the lower tank and discharge the fuel to the lower compartment of the upper tank and from which it is fed by gravity to the carburetor of the engine.

With the construction as just described the shifting of the valves is due solely to the actuation of the float by the rise and fall of the liquid between exactly predetermined levels. On the other hand, the lifting of the liquid is due to the suction, which varies according to the vacuum in the manifold. In the ordinary operation of a motor car there is a wide range of variation in manifold pressures, the highest vacuum being when the engine is idling and the lowest where the throttle is wide open and the engine is operating under heavy load. Such variation occasions a corresponding variation in the elevation of the fuel and the time when there is the least power for elevating the same. Moreover, the air which is withdrawn from the vacuum chamber of the tank carries with it vapor of the liquid fuel and the higher the vacuum in the tank the greater the vaporization, and consequently, the richer the mixture produced. It is the function of the carburetor of the

engine to properly proportion the ratio of fuel to air, and therefore, the mixture which is withdrawn from the vacuum tank and which varies in richness interferes with proper carburetion and proper operation of the engine. A further disturbance is occasioned by the alteration in the manifold pressures due to the alternating introduction of air from the vacuum tank and the cutting off of such supply of air.

It is the primary object of my invention to overcome the lack of uniformity in action due to the varying causes above described, and it is the further object to greatly simplify the mechanical construction. Thus, in place of operating the valves through a complex lever and spring mechanism actuated solely by the buoyancy of the float, I dispense with all levers and springs and control the valves through the conjoint action of hydrostatic and pneumatic pressures. This not only dispenses with numerous parts, but also avoids the large variations in action between low vacuum and high vacuum conditions in the manifold incident to the normal operation of the engine.

Another feature of improvement is in the connection between the upper and lower chambers of the vacuum tank. In this I have substituted for the normally closed check-valve a normally open valve which has the advantages; first, that the two chambers are normally in open communication and any expansion of liquid in the lower chamber will merely force it upward in the upper chamber; second, there is less restriction to the flow of liquid so that the discharge from the upper to the lower tank is more rapid; third, there is no danger of the clogging of the valve by foreign matter lodging between the same and its seat; fourth, the construction is simpler and can be manufactured at a lower cost. Other features of improvement will be more specifically referred to hereinafter.

In the drawings:

Figure 1 is a sectional elevation of the tank with the parts in position where the upper chamber is empty of liquid;

Figure 2 is a similar view showing the parts in normal position of operation when the vacuum is in communication with the chamber; and

Figure 3 is a similar view of the parts in

normal operation where the atmospheric air is in communication with the chamber.

A is the vacuum tank which has arranged in the upper portion thereof the inner receptacle B of smaller diameter, leaving an annular chamber C between the same and the outer tank and connected to the latter at its upper end by the flange D. E is a cap or head for closing both tanks, which is 10 suitably bored and chambered for the reception of the controlling valves and their connections.

Within the inner receptacle B is arranged a float F which is preferably only about one-half the weight of the displaced liquid. The float F is mounted upon a vertically extending stem, G, this being guided at its lower end in a suitable bearing H and at its upper end in a bearing I formed in the head E. 20 The upper end of the stem forms a valve J which engages a seat K in the head E controlling the vacuum connection. The area of the seat K and the opening therethrough is such that when the valve is seated and 25 there is atmospheric pressure within the receptacle B, the differential pressure acting upon the valve will supplement the flotation pressure of the liquid in sustaining the float. Thus the liquid within the receptacle. 30 B may fall to a considerable distance below the displacement level on the float before the weight of the latter will overcome the differential air pressure and withdraw the valve J from the seat K.

35 L is a valve within a chamber in the head E which is gravity-seated and controls an air vent port M for the receptacle B. This port M communicates with a passage N in the head which is connected with a down-turned conduit O outside of the tank and also communicates through a channel P with the annular chamber C between the tanks A and B. The valve L is pneumatically operated and to this end is provided with a 40 piston portion L' which is slidable in the cylindrical portion of the casing, while above this piston portion is a valve face L² for engaging a seat Q. This seat is formed on a plug Q' which forms a closure for the chamber containing the valve L, and the port Q² within the seat is connected by a passage Q³ with a chamber R. Within this chamber is a valve S which is guided in a hollow plug R' for closing the chamber R. The 45 valve S is arranged directly above the valve J and engages a seat S', while between the seats K and S' is a channel T forming the vacuum connection. This channel is connected through the fitting U with the conduit U' leading to the manifold of the engine. 50

With the construction of the various valves just described the vacuum of the manifold which is communicated through 55 the conduit U' and fitting U to the channel

T will, when either of the valves S or J is seated, cause a differential air pressure thereon corresponding to the area of their respective seats. The valve J is provided with an upward extension V, which before 70 said valve can close upon its seat will bear against the valve S and lift it from its seat. This unseating of the valve S will communicate the vacuum within the channel T to the chamber containing the piston L' and the 75 differential pressure acting upon said piston will lift the same, unseating the valve L and seating the valve L². The effect is therefore to open the atmospheric air connection to the receptacle B at substantially the same time 80 that the vacuum is cut off from said receptacle by the closing of the valve J. The seating of the valve, L², does not, however, completely prevent the passage of air through the port, Q², and thence past the 85 open valve, S, and through the passage T, to the source of suction, which is usually the intake manifold of the engine, for the reason that a bleed port is formed by a channel, L³, in said valve, L². This bleed 90 port is so restricted that it does not interfere with the retention of the valve, L², against its seat as long as the valve, S, is open; but upon the closing of said valve, S, said bleed port, L³, will admit air to defeat 95 the vacuum operating at the port Q, and permit the valve, Q², to drop away from its seat.

The upward extension V of the valve J is used for the performance of another important function, viz, that of a metering pin for variably restricting the port controlled by said valve. To this end the member V is of slightly tapering form so that when the valve J is closed to its seat, the vacuum port will be greatly restricted. On the other hand, as the valve J recedes from its seat the area of the vacuum port will be progressively increased, attaining its maximum when the member V is completely withdrawn from the port. This has the effect of increasing the area of vacuum connection to the chamber B as the float F lowers, with a maximum area when the float occupies its lowest position. It is, however, desirable to only use this maximum area where the vacuum in the manifold is very slight and under normal conditions to restrict the area of connection. This is accomplished by forming an enlargement G' on the stem G which closely fits within the bearing I and acts as a piston which is exposed to differential air pressures. Thus, when the valve J is first withdrawn from its seat by the downward pull of the float, the friction of the air passing between the piston L' and bearing I towards the vacuum port will retard the downward movement of the stem G and, in fact, will hold the valve J in close proximity to its seat. The valve is prevented from complete- 110 115 120 125 130

ly seating by the obstruction of the valve S, which latter is held to its seat by differential atmospheric and vacuum pressures. Therefore, under normal conditions the vacuum connection to the receptacle B will be highly restricted; but when under exceptional conditions the vacuum is weak and the pneumatic pressure upon the piston L' is thereby diminished, the valve J will be withdrawn 5 farther from its seat, which will enlarge the vacuum connection to the chamber B. This enlarged vacuum port will communicate with the chamber B through a lateral port I' in the bearing I which is uncovered when 10 the piston L' drops to its lowermost position.

It is usual to arrange between the upper and lower chambers of the vacuum tank a gravity seated check valve which is normally closed and is opened only by the pressure of 20 the discharging liquid. I have reversed this condition by employing a check valve that is normally open and is withdrawn from its seat by its own gravity. On the other hand, when there is a vacuum in the receptacle B, 25 the check valve must be closed, which is accomplished by the following construction.

W is a fitting in the bottom of the receptacle B which receives the guide bearing H for the stem G and which also has a valve seat W'. Below the valve seat W' is a chamber W² which contains a valve X, preferably formed of sheet metal and preferably of an inverted cup form. Below the chamber W² containing the valve X is a contracted neck Y which may be formed of a separate member connected with the fitting W by a spun-over flange Y'. The valve X will be arranged normally below the seat W' so as to provide a free passage for the liquid from 30 the receptacle B downward into the receptacle A. However, on account of the contracted neck Y, the whole fitting will be filled with liquid during the discharge from the upper to the lower receptacle. Thus 35 when through reversal of the valves J, S and L vacuum is placed in the upper receptacle, the atmospheric pressure in the lower receptacle will operate through the liquid column within the fitting W, reversing the direction of flow and carrying the valve X to its seat. The presence of this liquid within the fitting will thus greatly facilitate the movement of the valve so that a very slight change in pressure will cause either the 40 opening or the closing of the valve. When there is no liquid in the fitting, as where all the liquid in the upper receptacle has been drained out, then the enlarged vacuum connection to the receptacle B will cause the 45 rapid air current through the fitting W, this impinging against the cupped valve and thereby lifting it to its seat.

With the construction as above described, the complete operation is as follows: It will 50 be understood that the tank is connected in

the usual way with the low level supply tank as through a conduit Z to the intake manifold by the conduit U' and to the carburetor by the discharge conduit Z'. Assuming that the vacuum tank is empty, the float F will 55 be in its lowermost position as shown in Figure 1, in which position the valve J is withdrawn from its seat and the metering pin V is withdrawn from obstructing the vacuum port. The valve L is also seated, closing the vent port M. When the engine is started, the throttle being closed, the high vacuum will be communicated through the conduit U' to the chamber within the receptacle B. This will cause a rapid upward current of 60 air through the fitting W, which current impinging against the valve X will lift the same to its seat. As soon as the valve X seats, the high vacuum within the receptacle B will cause the lifting of the liquid from 65 the lower tank through the conduit Z and the filling of the receptacle B. As the level of the liquid rises in the receptacle B, the float F will be lifted by hydrostatic pressure, raising the stem G and piston G' 70 thereon so as to close the port I'. When this port is closed, the hydrostatic pressure on the float is supplemented by differential pneumatic pressure on the piston G', but the valve J is prevented from completely closing against its seat by the obstruction of the valve S which in turn is held seated by differential pneumatic pressure. Consequently, 75 after the valve J has been moved into proximity to its seat, it will remain stationary until the rise of liquid in the receptacle B will overcome the differential pneumatic pressure, unseating the valve S and seating the valve J. As soon as the valve S is unseated, the differential pressure thereon will 80 be neutralized so that it is only the weight of the valve that bears upon the stem G. On the other hand, the differential pressure upon the valve J will retain the latter to its seat even after the level of liquid in the receptacle B has dropped below the displacement level for the float. The higher the vacuum which is operating upon the valve J, the longer the float will be held from dropping, and consequently, instead of having absolutely fixed and determined high and low levels for the liquid, these will fluctuate according to vacuum conditions. If the vacuum is very light, the difference between the upper and lower positions of the float will 85 be slight and the reciprocations will be more rapid. On the other hand, if the vacuum is high, there will be a greater difference in levels and the reciprocation of the float will be slower.

When the valve J seats and the valve S is unseated, the vacuum communicated to the valve L² and piston L' will lift the valve L, opening the air port M and restoring atmospheric pressure within the receptacle B. 90

This will permit the valve X to drop by its own gravity away from the seat W, while the liquid within the upper receptacle B is free to flow past said valve into the lower tank. This continues until the liquid has reached a level where the weight of the float is less than the combined hydrostatic and pneumatic pressures, whereupon the float drops, unseating the valve J and permitting the valve S to seat. Vacuum connection is thus cut off from the port Q² and the bleed port L² will neutralize the vacuum, permitting the valve L to seat by gravity and to thereby close the port M. Vacuum is then again communicated to the receptacle B and the drop in pressure in this receptacle will cause a reversal of the liquid current in the fitting W, so that the valve X is lifted to its seat. The parts will remain in this condition until the hydrostatic pressure on the float will overcome both its weight and the differential pneumatic pressure upon the valve S and the cycle is repeated.

It has been stated that a disturbance to uniform carburetion is occasioned by the functioning of the ordinary vacuum tank, due to alteration in manifold pressures when the tank is alternately connected and disconnected. For instance, when the tank is connected with the manifold, the air admitted will reduce the vacuum and when it is disconnected, the vacuum will be increased. With my improvement this variation is largely eliminated by the admission of air from the external atmosphere through the bleed port L² into the manifold during the interval in which the tank is disconnected therefrom. If desired, the quantity of air so admitted can be made to exactly balance the quantity that is admitted from the vacuum chamber of the tank so that the carburetor will not be disturbed in its action by the shifting of the tank valves.

Another important feature of my invention is the acceleration in the discharge of liquid from the upper to the lower chambers of the tank due to an unbroken hydrostatic column. The fact that the valve X is normally open, together with the shape of the fitting W and the contracted neck Y thereof, tends to form a smooth flowing column of liquid instead of a broken stream. Therefore, when the lower tank is nearly empty, the length of this column will be much greater than when the lower tank is nearly full and the action in respect to the velocity

flow varies similarly to a siphon having a variable length of discharge. In other words, when the tank is nearest empty and there is the greatest necessity for refilling, the movement of the liquid from the upper receptacle is accelerated and when the lower tank is nearly full, the movement of the liquid from the upper receptacle is less rapid.

What I claim as my invention is:

1. In a vacuum tank having a connection with a source of suction, means for connecting said suction connection alternately with said tank and the external atmosphere to substantially balance the effect upon the pressure at the source of suction.

2. The combination, with a vacuum tank and a connection leading to a source of suction, of means operating during the interval in which said suction connection is disconnected from the tank to admit thereto a balancing volume of air.

3. In a vacuum tank provided with an upper and lower compartment, a valve-controlled port for liquid flow from the upper to the lower compartment, a conduit by which the liquid descends by gravity from said port to its discharge in the lower compartment, said conduit having flow capacity less than the valve-controlled port, so that the liquid in said conduit constitutes an unbroken column whereby the velocity of discharge is accelerated upon the lengthening of said column.

4. In a vacuum tank provided with an upper and a lower compartment, a discharge connection from said upper to said lower compartment, a normally open check-valve in said discharge connection, and a contracted neck below said check-valve for forming an unbroken liquid column and for normally maintaining liquid pressure on both sides of said valve.

5. In a vacuum fuel feeding system in combination with a receptacle provided with a liquid inlet, a suction connection and an atmospheric air connection, and a pneumatically operated valve controlling said atmospheric air connection, said valve having a bleed port formed therein, a valve controlling said suction connection, and a movable member operated by pneumatic and hydrostatic pressure for controlling said valves.

In testimony whereof I affix my signature:

WILFRED O. CHASE.
